UNITED STATES PATENT OFFICE

JESSE REDWINE, OF SAN FRANCISCO, CALIFORNIA

DESIGN FOR A LAMP

Application filed January 8, 1931. Serial No. 38,245. Term of patent 7 years.

To all whom it may concern:

Be it known that I, JESSE REDWINE, a citizen of the United States, residing at the city and county of San Francisco, and State of California, have invented a new, original, and ornamental Design for a Lamp, of which the following is a specification, reference being had to the accompanying drawing, forming part thereof.

In the drawings Fig. 1 is a front view of my lamp, Fig. 2 is a side view, and Fig. 3 is a plan view.

In further detail the lamp comprises a base 1 with a translucent shade in the form of an Indian tepee 2 through the open front of which is seen the figure of an Indian 3 stooping behind an incense bowl 4 and behind which Indian is the electric light bulb 5 of the lamp as dotted in Fig. 2, the circuit cord of which extends from the base.

I claim:

The ornamental design for a lamp substantially as shown and described.

JESSE REDWINE.
